CYLINDER PAPER MACHINE AND SUCTION ROLL FOR USE THEREIN

Filed Dec. 19, 1931

UNITED STATES PATENT OFFICE

1,998,046

CYLINDER PAPER MACHINE AND SUCTION
ROLL FOR USE THEREINCharles L. Ellis, Bradford Hills, Pa., assignor to
Downingtown Manufacturing Company, Downingtown, Pa., a corporation of Pennsylvania

Application December 19, 1931, Serial No. 562,134

16 Claims. (Cl. 92—39)

This invention relates to cylinder paper machines, and more particularly to the construction of cylinder paper machines adapted for the production of board.

5 An important object of the invention is the improvement of the several apparatuses shown in my prior application, Serial No. 489,215, filed October 16, 1930, for Board machines, and in the prior application of William H. Sutherland and 10 Charles L. Ellis, Serial No. 565,898, filed September 29, 1931, for Board machine, and to further generally improve cylinder paper machines employed in the manufacture of board to enable practical water extraction from the pulp web by 15 means of a suction roll directly cooperating with the web.

It has been proposed to employ suction rolls with cylinder paper machines for the purpose of extracting water from the felt and web and 20 sporadic attempts have been made to employ suction rolls which directly co-operated with the pulp web. Such devices were, however, extremely unsatisfactory due to the fact that a suction roll of ordinary construction co-operating directly with the pulp web has a tendency to draw 25 the particles of the pulp into the openings of the suction roll, thereby clogging these openings and interfering with the action of the suction roll and, furthermore, causing the pulp web to adhere 30 to the suction roll to an extent such that it could not be practically disengaged therefrom. Even 35 where successfully disengaged, the surface of the sheet is rough or pimply as a result of the increased suction action at the suction openings of the roll. Suction rolls may be employed with some slight success where they operate through 40 a felt and the formed pulp web is extremely thin as in the case of crepe paper or tissues. When, however, such rolls are employed through a felt with board or relatively heavy papers, the suction action has been found to be practically useless for the suction effort is insufficient to enable 45 the water to be drawn through the heavy paper web so that any water extraction accomplished by the roll must be accomplished by indirection; that is to say, by removal thereof from the felt and subsequent withdrawal by the felt of water from the web. Since, however, it is impossible 50 to use a suction roll through the felt without employing a second felt with the pick-up felt of cylinder machines where a press roll is associated with the suction roll, no pressing action can be obtained and, accordingly, the extent of water extraction from the felt is extremely slight. It 55 has, therefore, been the common practice where

suction rolls or water extractors are associated with the pick-up felt to employ a second felt. With the second felt, since it will naturally pick up a great deal of water and has at all times a relatively large water content, the actual water content of the combination passed through such suction presses is so increased that the efficiency of the suction action is counteracted.

5 In the prior applications above identified it has been disclosed that the felt with its attached web may be passed between a pair of pressure-engaged rolls, provided the pressure-engaged roll having engagement with the web is formed with a wire face, and it has, furthermore, been proposed to dry the sheet to an extent such that it may be passed directly to presses by the use 10 of a plurality of presses including such wire-faced rolls which have direct engagement with the pulp web prior to the time that it leaves the felt.

15 More specifically, objects of the present invention are first, the provision of a cylinder paper machine wherein the drying of the pulp web while still attached to the pick-up felt may be extended to a point such that the web may be 20 directly delivered to the first press; and second, the provision of a suction roll of such construction that it may be employed directly in engagement with the pulp web for the purpose of extracting water therefrom without damage to 25 the sheet.

30 These and other objects I attain by the construction shown in the accompanying drawing wherein, for the purpose of illustration, I have shown a preferred embodiment of my invention 35 and wherein:

Fig. 1 is a diagrammatic view showing a cylinder paper machine embodying my invention;

Fig. 2 is an enlarged transverse sectional view 40 through the suction roll;

Fig. 3 is a fragmentary diagrammatic view showing a modified construction of the suction press;

Fig. 4 is a characteristic fragmentary sectional view through the roll of Figs. 1 to 3;

Fig. 5 is a characteristic longitudinal section 45 through the roll; and

Fig. 6 is a fragmentary perspective of the press roll of one of the extractor presses.

50 Referring now to the drawing, and more particularly to Fig. 1 thereof, the numeral 10 generally designates vats each containing a cylinder mold 11 having a couch 12 cooperating therewith. 13 designates extractor presses each having a wire-faced press roll 13a directly engaging the 55

paper web formed by the cylinder molds upon the felt 14, and 15 designates the first main press of the machine.

In accordance with my invention, the felt 14, after leaving the last of the extractor presses 13, and with the web still attached thereto, is passed through a suction press 16 including a suction roll 17 of special construction more clearly shown in Figs. 2, 4 and 5.

10 Referring more particularly to Figs. 2, 4 and 5, it will be seen that the perforated roll 18 of this suction roll is longitudinally grooved to form ribs 19, the surfaces of which have spaced notches 20 receiving heavy reinforcing wires 21 which are placed in fairly close proximity to one another. Surrounding the reinforced roll is a relatively coarse wire covering 22 which is in turn surmounted by a fine mesh covering of wire cloth 23. In the construction shown in Figs. 20 1 and 2, this wire-cloth is permanently mounted upon the roll, although as will hereinafter become obvious, and as illustrated at 23—a in Fig. 3 it is not essential that this covering be permanently associated with the roll in any way except in that of traveling at the same speed as the roll. Suction roll 17 operates at the same speed as the felt 16 and has contact with its associated press roll 24 at a point overlying the final packing 25 of the suction box 26 of the 25 roll; that is to say, the packing which is last passed over by any given portion of the shell during its rotation. The suction effort exerted by the suction box tends to act directly upon the paper web W carried by the felt 16 and by 30 its action not only to withdraw water from the paper web but likewise to loosen the web from the felt to which it is attached and cause it to rest upon the wire covering 23. Beyond the final packing 25, in the direction of the rotation of the roll, a blow pipe or other suitable means for 35 producing an air blast is provided as indicated at 27 and the blast of air emitted thereby lifts the sheet from the wire 23 so that it may be freely passed to the press 15.

40 Due to the fact that the surface of wire 23 is very close and the paper web has already been acted upon by the extractor presses so that it is compacted and has little or no tendency to displacement of the fibres thereof, this web does not tend to enter into the meshes of the wire 23 so that the pimpling effect and adherence ordinarily present as a result of use of a suction roll in direct engagement with the sheet is entirely eliminated. Likewise, due to the use of this wire 45 face, great pressure can be brought to bear upon the suction roll through the associated press roll 24 with the result that the water extraction at the suction press 16 is very considerable and the sheet is prepared so that it may receive its final 50 pressing without any material loss in strength as a result of such pressing. It may be here pointed out that in handling a pulp web by the ordinary constructions employed in cylinder paper machines the pulp web has its greatest 55 strength at that time when it has just been completed by the final cylinder mold; that is to say, if the paper machine is stopped and samples are taken of the pulp web immediately following the final cylinder mold at varying stages in the 60 preliminary pressing and after final pressing, it will be found that the web when dry has its greatest pop test in the sample taken immediately following the final cylinder mold and before any pressing. This is undoubtedly due to 65 the fact that the water included in the web

causes the web when subjected to great pressures, as in pressing, to shift as regards the "lay" of its fibres, for the press tends to expel water from that portion of the web held in the nip of the rolls through the web and this water acting upon the fibres of the web tends to cause them to assume positions longitudinal to the web. The actual pressing operation, when performed in the ordinary manner, has doubtless the same tendency. Board produced without 10 preliminary pressing and simply by the use of extractor rolls has a much greater pop test than board produced from similar materials and under similar circumstances with preliminary pressing. However, in order to sufficiently dry board by 15 the use of extractor presses alone it is necessary that too great a number of extractor presses be employed. This I eliminate and at the same time facilitate removal of the web by the use of the suction apparatus just described. 20

Attention is directed to the fact that the ribs produced by the grooves 19 together with the reinforcing structure employed serve to distribute the suction area in a direction longitudinal to the shell while resisting circumferential distribution of this suction effort. Since the ribs themselves are relatively narrow and, therefore, offer slight obstruction, substantially the entire area of the wire covering 23 or 23—a overlying the suction box will be affected. This uniform distribution throughout the suction area, instead of confinement thereof to the relatively small number of openings, effectually prevents any such suction effort being exerted upon the paper as will cause the same to cling to the wire or to be 30 deformed by being drawn into the interstices of the wire.

Since the construction employed is, obviously, capable of modification without departing from the spirit of my invention, I do not wish to be 40 understood as limiting myself thereto except as hereinafter claimed.

I claim:

1. In a cylinder paper machine comprising a plurality of cylinder molds, a pick-up felt associated with said molds and collecting the paper web therefrom, and means for extracting water from the web comprising a suction press through which the felt and web pass, said suction press including a suction roll having a cylindrical wire face 45 in direct engagement with the web. 50

2. In a cylinder paper machine, a plurality of cylinder molds, a plurality of extractor presses and a suction press and a single felt passing successively over said cylinder molds through said 55 extractor presses and through said suction press, each of said extractor presses and suction press including a roll having a cylindrical wire face directly engaging the paper web accumulated by the felt in its passage over the cylinder molds. 60

3. In a cylinder paper machine comprising a plurality of cylinder molds, a pick-up felt associated with said molds and collecting the paper web therefrom, and means for extracting water 65 from the web comprising a suction press through which the felt and web pass, said suction press including a suction roll having a cylindrical wire face in direct engagement with the web, the suction box of the suction roll being disposed to exert 70 its suction through the wire entirely in advance of the nip between the suction roll and its associated press roll.

4. In a cylinder paper machine comprising a plurality of cylinder molds, a pick-up felt asso- 75

- ciated with said molds and collecting the paper web therefrom, and means for extracting water from the web comprising a suction press through which the felt and web pass, said suction press including a suction roll having a wire face in direct engagement with the web, the wire face being directly carried by the roll, the suction box of the suction roll being disposed to exert its suction through the wire entirely in advance of the 5 nip between the suction roll and its associated press roll.
5. In a cylinder paper machine, a plurality of cylinder molds, a plurality of extractor presses and a suction press and a single felt passing successively over said cylinder molds through said extractor presses and through said suction press, each of said extractor presses and suction press including a roll having a wire face directly engaging the paper web accumulated by the felt in 10 its passage over the cylinder molds, the suction box of the suction roll being disposed to exert its suction through the wire entirely in advance of the nip between the suction roll and its associated press roll.
- 20 6. In a suction press, a suction roll comprising a perforated shell, an interiorly arranged suction box co-operating with the shell, a cylindrical wire facing for and attached to the shell, means spacing the shell and facing constructed and arranged to permit distribution of suction effort exerted through openings of the shell substantially uniformly through the portions of the facing overlying the suction box and a press roll co-acting with said suction roll.
- 30 7. In a suction press, a suction roll comprising a perforated shell having longitudinally-extending ribs, a wire facing for the shell operatively supported from said ribs and a press roll co-acting with said suction roll.
- 40 8. In a suction press, a suction roll comprising a perforated shell having longitudinally-extending ribs, a heavy wire operatively supported from said ribs, a relatively light wire facing for the roll supported from said heavy wire and a press roll co-acting with said suction roll.
- 45 9. In a suction press, a suction roll comprising a perforated shell having longitudinally-extending ribs, circumferentially-extending heavy reinforcing wires supported by said ribs, a heavy sieve wire supported by said circumferentially reinforcing wires, a relatively light sieve wire facing for the roll supported from said heavy sieve wire and a press roll co-acting with said suction roll.
- 55 10. In a suction press, a suction roll comprising a perforated shell having longitudinally-extending ribs, circumferentially-extending heavy reinforcing wires supported by said ribs, a heavy sieve wire supported by said circumferentially reinforcing wires, a relatively light sieve wire facing for the roll supported from said heavy sieve wire, the circumferentially-extending reinforcing wires being engaged in notches formed in the 60 ribs whereby to dispose the inner face of the heavy sieve wire in close proximity to the outer ends of the ribs and a press roll co-acting with said suction roll.
11. In a cylinder paper machine comprising a plurality of cylinder molds, a pick-up felt associated with said molds and collecting the paper web therefrom, means for extracting water from the web comprising a suction press through which the felt and web pass, said suction press including a suction roll having a cylindrical wire face in direct engagement with the web, said suction 10 roll comprising a perforated shell and an interiorly arranged suction box, and means supporting the wire face from said shell constructed and arranged to permit distribution of suction exerted through the perforations of the shell substantially uniformly throughout the area of the wire face aligned with the suction box.
- 15 12. In a cylinder paper machine, a cylinder mold, a pick-up felt associated with said mold and collecting a paper web therefrom, and means for extracting water from the web comprising a suction press through which the felt and web pass, said suction press including a suction roll having a cylindrical wire face in direct engagement with the web.
- 20 13. In a cylinder paper machine, a cylinder mold, an extractor press and a suction press, and a single felt passing successively over said cylinder mold, through said extractor press, and through said suction press, each of said extractor and suction presses including a roll having a cylindrical wire face directly engaging the paper web accumulated by the felt in its passage over the cylinder mold.
- 25 14. In a cylinder type of paper machine including a pick-up felt for transferring a fibrous web from the forming molds, means for extracting water from said felt and web carried thereon comprising a suction roll having a defined suction area, a foraminous carrier passing over said suction area and means located outside of said suction area for bringing said felt and web into direct cooperation with said carrier and suction roll for the application of suction through said carrier to said felt and web.
- 30 15. In a cylinder type of paper making machine, means for removing water from the paper web while on the pick-up felt comprising a suction roll, a foraminous carrier entrained around said suction roll, and means located outside of the 40 suction area of said suction roll for directly contacting without pressure the fibrous web against said foraminous carrier when traveling over the suction area of said suction roll.
- 45 16. In a cylinder paper machine comprising a plurality of cylinder molds, a pick-up felt associated with said molds and collecting the paper web therefrom, means for extracting water from the web comprising a suction roll over which the felt and web pass, said suction roll having a wire face in direct engagement with the web, the wire face being directly carried by the roll, and means to maintain the paper web in contact with the surface of the suction roll while passing over the suction box of the roll.

CHARLES L. ELLIS.
